DESIGN FOR A SPOON OR OTHER ARTICLE OF FLATWARE

Samuel C. Friedman, New York, N. Y.

Application October 29, 1945, Serial No. 123,259

Term of patent 14 years

(Cl. D54—12)

To all whom it may concern:

Be it known that Samuel C. Friedman, a citizen of the United States of America and resident of the city and State of New York, has invented a new, original, and ornamental Design for a Spoon or Other Article of Flatware, of which the following is a specification, reference being had to the accompanying drawing, forming part thereof, in which,

Fig. 1 is a top plan view of a spoon embodying my new design;

Fig. 2 is a bottom plan view of the portion of the handle of the spoon shown in Fig. 1;

Fig. 3 is a side elevational view of the spoon shown in Fig. 1; and

Fig. 4 is a cross-sectional view slightly enlarged and taken substantially along the line 4—4 of Fig. 1.

I claim:

The ornamental design for a spoon or other article of flatware, substantially as shown.

SAMUEL C. FRIEDMAN.
